UNITED STATES PATENT OFFICE.

EDWARD C. POST, OF CHICAGO, ILLINOIS, ASSIGNOR TO VAPOR CAR HEATING COMPANY, INC., OF CHICAGO, ILLINOIS, A CORPORATION OF NEW YORK.

COUPLER.

Application filed March 9, 1922. Serial No. 542,297.

To all whom it may concern:

Be it known that I, EDWARD C. Post, a citizen of the United States, residing at Chicago, in the county of Cook and State of Illinois, have invented certain new and useful Improvements in Couplers, of which the following is a specification.

My invention relates to a hose coupling, especially a coupling intended for detachably uniting the hose or equivalent flexible, metal, tubular elements on the ends of the train pipes of adjacent cars of a railroad train.

The primary object of my invention is to provide a novel, simple coupling of economical construction of which the mating members may be brought into a preliminary engagement by a lateral movement of one member toward the other (without the usual rocking or angular movements characteristic of the gravity type of coupling) and then drawn into fluid tight relation with their gaskets pressed one against the other to complete the coupling operation.

More specifically, my invention contemplates the formation of one of the elements of the coupling with a projecting lug and the other with a sliding member which is forced into engagement with said lug, so as to draw the couplers together, by means of a wedge, cam, eccentric, or equivalent device. By the term "coupling" I intend to include both mating members. The term "coupler" is used to denote one of these members. The coupling may consist of two members each constructed in accordance with my present invention, but a single coupler so constructed may be mated with another coupler differently designed so long as the other coupler is provided with engaging parts of suitable configuration and properly placed. In one form of the invention the coupler is shown as adapted for mating with any of the standard types of gravity hose couplers now in general use on the steam railroads for making the connection between the steam train pipes of passenger cars.

The invention consists in the new and improved constructions, arrangements and devices, to be hereinafter described and claimed, for carrying out the above stated objects and such other incidental objects as will be referred to in the following description of the preferred embodiments of

the invention shown in the accompanying drawings.

In the drawings:

Fig. 1 is a side elevation of a hose coupling comprising a coupler, constructed in accordance with this invention, mated with a gravity hose coupler of the S-4 type.

Fig. 2 is a plan view of the coupling shown in Fig. 1.

Fig. 3 is a view, in perspective, of the sliding member forming a part of the improved coupler shown in the preceding figures.

Fig. 4 is a sectional plan view taken on line 4-4 of Fig. 1.

Fig. 5 is a view, in perspective, of the improved coupler shown in Figs. 1, 2 and 4, the usual gasket being omitted.

Fig. 6 is a view, in perspective, of the wedge or actuating device for moving the sliding member.

Fig. 7 is a plan view, with certain parts in section, of a coupling consisting of two identical couplers embodying my invention in a modified form.

Fig. 8 is a side elevation of the coupling shown in Fig. 7.

Fig. 9 is a view, in perspective, of the sliding member employed in the form of the invention shown in Figs. 7 and 8.

Fig. 10 is a fragmentary view, in elevation, of the sliding member showing the other side of the same from that shown in Fig. 9, and

Fig. 11 is a perspective view of the actuating cam for moving the sliding members shown in the preceding four figures.

Referring first to Figs. 1 to 6 inclusive, A designates a gravity coupler of the S-4 or safety type, which is well known in the art and does not require description. B is a coupler constructed in accordance with my invention and adapted to mate with an S-4 coupler or, in fact, with any of the common types of gravity couplers in use on the railroads of the United States.

The coupler B comprises a head 10 formed with a fluid port 11 in which is arranged any suitable type of gasket 12, the gasket forming no part of my invention. This gasket is adapted to be forced against a similar gasket arranged in the port of the coupler A. On one side of the coupler head 10 is formed an undercut lug 13 providing

an arcuate cam 14 adapting it for engagement by the projection 15 on the arm 16 of coupler A. Projecting forwardly from the other side of the head 10 of coupler B is an 5 arm 17 formed with outstanding parallel flanges 18, 19 having slots 20, 21 therein, the arm itself being formed near its outer end with an opening 22 therethrough. Slidably arranged between the guide flanges 10 18, 19 is a member 23 formed at its forward or outer end with an enlarged head 24 which lies on the inside of arm 17 projecting through opening 22. This part of the sliding member 23 is formed with an undercut, 15 arcuate portion 25 adapted to engage with the undercut lug 26 formed on the side of coupler A. At the lower end of the arcuate cam 25 is a rearwardly projecting lug 27 upon which the under surface of lug 26 is 20 adapted to bear. The sliding member 23 is formed with a vertical slot 28 through which, and through the slots 20, 21 in flanges 18 and 19 extends a wedge 29 preferably formed at its lower end with a retaining lug 25 30. Preferably a coiled spring 31 is interposed between a web 32 on the head 10 and the inner or rear surface of the sliding member 23, the web and sliding member being formed with centering studs 33, 34 for the 30 spring.

The sliding member 23 is applied to its operative position by inserting the slotted end through the opening 22 of the arm 17 so that the ends of the enlarged head 24 35 bears against the inner surface of the arm 17 and the flat inner surface of the member 23 slidably engages with the outer surface of the arm 17. The wedge 29 when inserted in the slot 28 prevents any appreciable lateral movement of the sliding member.

The head 10 is shown as provided with a locking link 35 pivoted in a lug 36 formed on the top of the head. The outer bent end 37 of this link is adapted to engage a 45 lug 38 on the coupler A. This form of locking device is the one commonly employed on an S-4 coupler and its use in connection with the improved coupler of my invention is optional.

50 In Figs. 7 to 11 inclusive, I have shown a coupler which differs from the coupler B, just described, in two respects: In the first place, the coupler is not designed for mating with standard gravity type couplers so 55 that the engaging parts may be simplified from the manufacturing standpoint. In the second place, a rotary cam instead of a wedge is employed for actuating the movement of the sliding member. These two features are quite independent of each other.

60 The coupling shown consists of two identical couplers C and D. Each of these couplers consists of a head 39 formed on one side with an undercut lug 40 and on the 65 other side with a forwardly projecting arm

41 having outstanding flanges 42, 43 between which is arranged a sliding member 44 provided at its forward end with a head 45 projecting through an opening 46 in the arm and formed with an undercut curved 70 lug 47 adapted to engage the lug 40 on the mating coupler. The rear portion of member 44 is formed with a recess 48 and with upper and lower slots 49, 50. 51 is a cam or eccentric arranged in recess 48 on a stud 75 52 which is fixed by cotter pin 53 in the flanges 42, 43 and extends through slots 49, 50 in member 44 and through a perforation 54 in the cam 51. The latter is provided with a handle 55 and to allow the necessary 80 amplitude of movement to the cam the back wall 56 of member 44 is cut away, as indicated at 57, and the side of member 44 grooved out, as indicated at 58. The cam 51 is adapted to bear against the back wall 56 85 of member 44 and against a surface 59 thereof defining the recess 48 at its forward side.

The sliding member 44 of this form of the device is applied to its operative position in substantially the same manner as described in connection with the sliding member 23 of the form shown in Figs. 1 to 6 of the drawings, and the flat inner surface 44^a of said member is held in sliding 90 engagement with the side of the coupler so as to prevent any appreciable angular or lateral displacement.

Operation: With either type of coupler a preliminary engagement of the coupler 100 with the mating coupler is effected, without any rocking or angular movement of said elements, by moving one toward the other sidewise. The hook-like portion of the sliding member engages the undercut 105 lug on the other coupler. In the type of coupler shown in Figs. 1 to 6 inclusive, the under side of lug 26 bears against the projection 27 on the sliding member 23 so as to keep the couplers substantially in alignment. With this type of coupler the engagement of the mating elements is completed by driving down wedge 29. This forces the sliding member toward the head 10, compressing spring 31, thus causing the 115 couplers to be drawn toward each other until their gaskets 12 are brought into steam-tight relationship with each other. Ordinarily these gaskets are made of a material which expands under the temperature 120 of steam so that (assuming the coupler is used on the steam train line) a tight joint is insured. To uncouple the couplers wedge 29 is driven upwardly and spring 31 forces the sliding member 23 outwardly so that one 125 coupler head may be disengaged from the other by a lateral movement.

In the form of the invention shown in Figs. 7 to 11 inclusive, the coupler heads are drawn together, after the preliminary 130

engagement has been made, by rotating cam 51 from left to right (Fig. 7). When the preliminary engagement is made the cam 51 will be turned so that handle 55 lies in the recess 58. The cam is rotated to the right as far as is necessary in order to bring the gaskets of the couplers into intimate contact. The movement of the sliding member 44 is positive in both directions. No spring 10 is required.

While I have described my invention in certain preferred embodiments, it is realized that modifications might be devised without departure from the principles of the invention. Therefore I wish it to be understood that the invention is not to be considered as limited to the particular constructions, arrangements and devices shown and described except so far as the claims hereto appended 20 are specifically so limited.

I claim:

1. For use as an element of a hose coupling, a coupler head having a member slideable thereon adapted to engage the mating coupler, and a wedge extending through said member and a part of the coupler for forcing said member in a direction to draw the couplers together.

2. For use as an element of a hose coupling, a coupler comprising a head formed at one side with a forwardly projecting arm, a member slideable lengthwise of said arm and adapted to engage the side of the mating coupler, and means for holding said member in position with capacity for said lengthwise movement and for forcing said member toward said head so as to draw the couplers together.

3. For use as an element of a hose coupling, a coupler having a member slideable thereon, formed with a slotted portion and adapted to engage the mating couplers, means extending into the slotted portion of said member to hold it in place with capacity for said sliding movement and to force said member in a direction to draw the coupler together, and a spring which is stressed by said movement of said member.

4. For use as an element of a hose coupling, a coupler comprising a head formed at one side with a forwardly projecting arm having parallel guide flanges, a member slideable between said flanges, formed with a slotted portion and adapted to engage the side of the mating coupler, and means extending into the slotted portion of said member to hold it in place with capacity for said sliding movement and to force said member toward said head to draw the couplers together.

5. For use as an element of a hose coupling, a coupler head having a member slideable thereon adapted to engage the mating

coupler, and an actuating device extending through said member and a part of said coupler for forcing said member in a direction to draw the couplers together.

6. For use as an element of a hose coupling, a coupler comprising a head formed at one side with a forwardly projecting arm having parallel guide flanges, a member slideable between said flanges and adapted to engage the side of the mating coupler, and an actuating device extending through said flanges and member for forcing the member in a direction to draw the couplers together.

7. A coupler for use as an element of a hose coupling, comprising a head formed with a port therethrough, a lug on one side of said head, an arm forwardly projecting from the other side and formed with guide flanges, a member slideable between said guide flanges and adapted to engage the mating coupler, and an actuating device extending through said flanges and member to hold said member in place and force the member in a direction to draw the couplers together.

8. A coupler for use as an element of a hose coupling, comprising a head formed with a port therethrough, a lug on one side of said head, an arm forwardly projecting from the other side and formed with guide flanges, a member slideable between said guide flanges and adapted to engage the mating coupler, and an actuating device extending through said flanges and member to hold said member in place and force the member in a direction to draw the couplers together, said member and lug formed with arcuate cams adapting the coupler for mating with couplers of the gravity type.

9. A coupler for use as an element of a hose coupling, comprising a head formed with a port therethrough, a lug on one side of said head, an arm forwardly projecting from the other side and formed with guide flanges, a member slideable between said guide flanges and adapted to engage the mating coupler, and a wedge extending through said flanges and member for forcing the member in the direction to draw said couplers together.

10. A coupler for use as an element of a hose coupling, comprising a head formed with a port therethrough, a lug on one side of said head, an arm forwardly projecting from the other side and formed with guide flanges, a member slideable between said guide flanges and adapted to engage the mating coupler, a wedge extending through said flanges and member for forcing the member in the direction to draw said couplers together, and a spring interposed between said member and head adapted to be compressed by the engaging movement of said wedge.

EDWARD C. POST.
